COMMUTATOR TRUING MECHANISMS

William S. Green, Waukesha, Wis.

Application October 29, 1934, Serial No. 750,512

4 Claims. (Cl. 29—27)

My invention relates to improvements in commutator truing mechanisms.

The object of my invention is to provide a machine tool having special devices to accomplish the truing and undercutting of commutators, especially such commutators as form the parts of armature assemblies found in the starters and generators of automotive vehicles.

More particularly stated, it is the object of my invention to provide a machine tool in the general configuration and having some of the general characteristics of a lathe, but provided with work holding chucks and special tools to be used in combination therewith for accomplishing a series of armature truing and conditioning operations.

In the drawing:

Figure 1 is a plan view of my improved commutator truing mechanism, with an armature commutator in position for a truing operation.

Figure 2 is a front elevation of the structure shown in Figure 1.

Figure 3 is a section on line 3—3 of Figure 2, but showing the undercutting device in position for operation.

Figure 4 is a radial section through my improved chuck.

Like parts are identified by the same reference characters throughout the several views.

My improved commutator truing and conditioning mechanism is incorporated in a device which, in its major structural elements, comprises a somewhat conventional lathe frame or bed 10, a tailstock 11 longitudinally adjustable along the bed, a headstock 12, and a motor support frame 13 for a motor 14.

The improvements which I have incorporated in the general structure described above are to be found in the chucks 15 and 16 mounted respectively in the tailstock and headstock, and in the structure shown most clearly at the left of Figure 3 and comprising mechanism indicated generally at 17 for undercutting the insulation between commutator bars, as will hereinafter be described.

In the use of my improved mechanism, an armature 18 on its own shaft 19 is mounted between the headstock and tailstock 11 and 12 for rotation by a belt 20 which passes over pulley 20' upon motor shaft 21, and also passes around the body of the armature 18. Belt 20 is tightened by the weight of the motor 14 upon its frame 13, which is in pivotal relation to a slide rod 22 extending along one side of the bed 10.

In the event that the motor 14 is excessively heavy so as to exert too great a tightening effect

upon the belt 20, adjustable stop 23 in threaded engagement with the frame 13 may be adjusted to contact with the bench (not shown) or other support for my mechanism.

Headstock and tailstock chucks

The tailstock 11 and the headstock 12 are provided with bearing sleeves 24 and 25, respectively, in which chuck tubes 26 are receivable, and each of the chuck tubes is provided at its interior or work holding end with a radially outwardly extended flange 27. There is thus provided within the tubes 26 ample room for the reception of the ends of the armature shaft 19 and the means for adjusting and centering the shaft 19 from the chuck mechanism about to be described.

The flange 27 upon the tube 26 is radially bored at spaced points 28 about its circumference for the reception of dogs 29, which are of sufficient length to contact on shaft 19 of an armature, and to extend therefrom to a rounded extremity 30 which may contact the interior face of conically shaped chuck ring 30' which is in threaded engagement at 31 with the exterior of the tubes 26.

Dog springs 32 secured to the flange 27 intermediate the dogs 29 extend arcuately, as shown in Figure 4, through apertures in the outer ends of the dogs 29 and are of such characteristics as to normally thrust the dogs radially outwardly against the interior surface of the chuck ring 30', and it will be apparent from the above description that I have provided in my chuck a rapid action centering or chucking device, since rotation of the chuck ring 30' upon the tube 26 will, in the one direction, thrust the dogs inwardly into contact with a shaft 19, or, upon counter-rotation of the chuck ring 30', will permit the springs to withdraw the dogs 29 from contact with the shaft, and since the interior surface of the chuck ring 30' is a true cone and the dogs are of equal length and accurately radially positioned, a shaft 19 must necessarily be accurately centered when the dogs are brought into contact with it simultaneously by the thrusting action induced by the crowding of the inner surface of the chuck ring against the outer ends of the dogs.

Tool holder

The headstock 12 is extended at 40 toward the forward side of my mechanism to provide a mounting for spaced carriage rails 41 and 42, which extend through tool carriage 43 which is apertured to receive them. Between the carriage rails 41 and 42 the portion 40 of the headstock is pro-

vided with receptor 44 to receive a threaded carriage actuator 45 provided with a crank arm 46. This carriage actuator 45 is in threaded engagement with the tool carriage 43, and rotation of 5 the carriage actuator, which is longitudinally immovable with respect to the receptor 44, results in the adjustment of the tool carriage upon the carriage rails. A tool holder 47 is adjustable by means of a knurled knob 47' with reference to the 10 tool carriage 43 radially of the center of the chuck tubes 26, and a set screw and lever, as shown at 48, may be used to positively position the tool holder when the proper adjustment thereof has been secured. It is thus possible, by means of 15 the tool carriage adjustment and the tool holder adjustment, to position a tool 49 with reference to a commutator 50 or armature 18, so that a truing operation upon the individual commutator bars may be performed while the motor 14 with 20 its pulley 20' causes the rotation of the armature 18 by means of the belt 20.

Undercutting mechanism

Opposite the tool carriage 43 or rearwardly of 25 the machine, and rearwardly of the armature 50, I provide a spindle support 60 mounted upon a vertical post 61 extending through a bracket 62 receivable upon and capable of sliding upon the bed 10, as shown distinctly in Figure 3. The post 30 61 is undercut at 63 to receive the head 64 of an adjusting screw 65 in threaded engagement with the bracket 62, and since the post 61 is vertically slidable through the bracket 62 the vertical adjustment of the adjusting screw will so position the 35 head 64 thereof within the undercut portion of the post 61 as to positively position the height of the spindle support 60.

The spindle support 60 is provided at 66 with a spindle rotatable in the support. This spindle 40 is provided at one end with an undercutting tool 67 and at the other end with a spindle pulley 68. A boss 69 on the side of the support 60 provides mounting for a pair of idler pulleys 70 and 71, so disposed respectively as to receive a belt 72 passing to and from a pulley 68, and to and from pulley 20' when the motor is slidably moved with its frame 23 upon rod 22 to dispose the pulley 20' opposite the support 60.

The support 60 is rotatable upon the vertical 50 axis of the post 61 which rotates positively therewith, and in its rotative adjustment with the post 61 may be positively positioned by a set screw 73.

A control handle 75 pivoted at 76 upon a pin secured to the bed 10 is connected to the bracket 55 62 by means of a link shown at 77 in dotted lines in Figure 1, whereby the operator of my improved mechanism may slide the bracket along the bed, thus sliding the support 60 and the spindle 66 longitudinally of the bed for forcing the undercutting tool longitudinally of an armature mounted in the chucks above described. When the undercutting tool is not being used the belt 72 may be removed from the pulleys and the spindle may be 60 swung around to the position shown in Figure 1, where it may be secured against rotation by the set screw 73.

From the above description it will be apparent 70 that I have provided in one mechanism facilities for rapidly and accurately truing and undercutting an armature commutator. The rapid action of the chucks above described permits the operator to quickly center an armature in position for

the reception of rotative power from the belt 20 when the motor is positioned upon the rod 22 therefor, and the tool 49 is easily and readily brought into position for a cutting operation to true the commutator as illustrated clearly in Fig. 5 figures 1 and 2.

When a truing operation has been accomplished the belt 20 may be removed from the pulley 20', and the belt 72 may be extended about the pulley 20'. The motor may then be moved to position 10 the pulley 20' opposite the support 60, and the support 60 may be rotatably moved to the position shown in Figure 3 to dispose the undercutting tool 67 in a groove between the commutator bars of the commutator. The belt 72 may then 15 be laced over the pulleys 70 and 71 and over the pulley 68 on the spindle 66 to rotate the undercutting tool, and the control handle 75 may be oscillated to cause reciprocation of the support and its associated mechanism within the limited 20 range necessary for the undercutting operation.

I claim:

1. In a device of the character described a bed and a headstock and tailstock spaced thereon for reception of work to be revolved, a motor supported from the bed and adjustable longitudinally thereof, a tool holding carriage supported from the headstock and a tool holding spindle supported from the bed and swingable to and from working position, the spindle being provided with 25 power connections engageable with the motor when the motor is adjusted along the bed to a position of alignment therewith.

2. In a device of the character described a bed and a headstock and tailstock spaced thereon for 30 reception of work to be revolved, a tool holding carriage adjustably supported from the headstock and provided with a tool for operation upon the work in the rotation thereof, and a tool holding spindle supported from the bed and swingable 35 to and from a position for operation upon the work when the work is stationary in the stocks and a motor adjustably mounted from the bed and provided with power connections alternatively usable in various adjustments of 40 the motor, whereby to rotate the work or operate the tool in the spindle.

3. In a device of the character described a bed and a headstock and tailstock spaced thereon for 45 reception of work to be revolved, a tool holding carriage adjustably supported from the headstock and provided with a tool for operation upon the work in the rotation thereof, a tool holding spindle supported from the bed and swingable 50 to and from a position for operation upon the work when the work is stationary in the stocks, power connections alternatively connectible to the work or to said spindle, said power connections including a motor device mounted for adjustment longitudinally of the bed and 55 provided with a pulley to be thereby positioned operatively opposite the spindle or the work to be revolved.

4. An armature commutator truing device including chucks for reception of the armature, a 60 motor provided with a pulley and belt to engage the armature whereby to rotate it, and a tool spindle support provided with a pulley and tool holding spindle adjustable whereby to dispose the pulley in belt alignment with the pulley on 65 the motor.

WILLIAM S. GREEN.
